UNITED STATES PATENT OFFICE.

BENSON FRANK FORD, OF NEAR MARION, IOWA.

PUMP HANDLE.

1,412,611.

Specification of Letters Patent. Patented Apr. 11, 1922.

Application filed May 18, 1921. Serial No. 470,722.

To all whom it may concern:

Be it known that I, BENSON FRANK FORD, a citizen of the United States, residing near Marion, in the county of Linn, 5 State of Iowa, have invented certain new and useful Improvements in Pump Handles; and I do hereby declare the following to be a full, clear, and exact description of the invention, such as will enable others skilled in the art to which it appertains to 10 make and use the same.

This invention relates to pumps, and more particularly such as are operated by wind power, as well as by hand, and the object of 15 the invention is to make it possible to easily and quickly connect, or disconnect the handle with the pump-rod, even while said rod is moving.

The invention is fully disclosed in the description and claims following, reference being had to the accompanying drawing, in 20 which:—

Fig. 1 is a side elevation of my improved pump-handle as applied to a pump of a familiar type. Fig. 2 is an elevation of the handle as seen from the pump-ward side, and showing a fragment of the pump-rod in position. Fig. 3 is a fragmentary side elevation, showing the handle in position for 25 engagement with the pump-rod. Fig. 4 is a side sectional view, showing details of the latch.

In the drawing, the numeral 5 denotes the upper end of a pump cylinder or casing, to 30 which is attached a fulcrum casting 6 provided with an upstanding guide 7 for the pump-rod 8. These may be of the usual construction, except that the pin 9 which engages the pump-handle is permanently 35 cured in the pump-rod, and projects each side thereof, as shown in Fig. 2.

To the fulcrum is pivoted a link 10, connecting with the handle 11 in the usual way. The handle has a forked head to straddle 40 the pump-rod, but the upper portion of this head 12 is cut away central to the hole 13 which engages the pump-rod pin. At 14 is pivoted a forked lever 15 whose jaws are provided with half-holes at 15^a, and are laterally flush with the head, so as to play 45 freely in the rod-guide. When in operative position, as shown in Fig. 1, the permanent stud of the pump-rod is held between the jaws and the head, and serves the same purpose as the ordinary pin or bolt in the hole 50 of an undivided head. The long arm of the

forked lever takes a somewhat shorter curve than the handle, and at 15^b unites to form a single tail-piece 15^c, standing out somewhat from the under side of the handle. To 60 the handle opposite this end-piece is pivoted a latch-lever 16, preferably forked to straddle the handle as well as the engaging end of the tail-piece. A spring 17 holds the latch in engaging position, and a stop 18 65 limits its movement under spring pressure. The latch is disengaged by a grasp of the hand, and may be engaged by a similar grasp applied to the lever near the tail end, the curved end of the tail-piece at 15^d, and the 70 curved shoulder 16^a of the latch-lever permitting the parts to snap together in a manner that will be readily understood. In practice the engagement is made in the manner indicated in Figs. 1 and 3. With the 75 jaws open, as shown in Fig. 3, the operator catches the pump rod stud between them, and pushes the handle inwardly to the extreme position shown in Fig. 1. The curve of the main lever then abuts against the fulcrum, and is forced to the latching position. This as well as the disengagement of the 80 handle may be easily effected while the pump-rod is in motion, and is the work of but a moment. This dispenses with the necessity of stopping the pump-rod to insert a pin, or making a difficult connection, by means of a pin with the rod in motion, under 85 conditions when such an operation is possible.

It is to be noted that a little wedging inclination is given to the latch shoulder at 16^b, so that the constant pressure of the spring tends to hold the main lever more tightly under the vibration to which it may 95 be subjected.

Having thus described my invention, I claim:

1. A pump-handle having a head divided across the pivot-hole, a similarly formed 100 jaw pivoted to the handle, and a latch-lever to hold the jaw in operative position.
2. A pump-handle having a head divided across its pump-rod pivot hole, a lever pivoted to the handle, and having a similarly 105 formed pivot-jaw, and a latch-lever connecting with the handle and adapted to engage the free end of the jaw lever.
3. A pump-handle having a head divided across its pump-rod pivot-hole, a lever with 110 similarly formed jaws pivoted to the handle, and having its longer arm curved in-

wardly of the handle so as to abut on some projecting part of the pump, and a latch adapted to snap into engagement with said long arm when it is forced against such projection.

4. A pump-handle having a head divided across its pump-rod pivot-hole, a lever with similarly formed jaws, pivoted to the handle, a latch to engage the other end of the lever, 10 and a spring to force it into such engage-

ment, the engaging faces being slightly inclined, whereby the spring tends to continuously tighten the engagement.

In testimony whereof I affix my signature in presence of two witnesses.

BENSON FRANK FORD.
